UNITED STATES PATENT OFFICE

JOHN R. GOULD, OF ALDWYCH, LONDON, ENGLAND, ASSIGNOR TO WESTERN ELECTRIC COMPANY, INCORPORATED, OF NEW YORK, N. Y., A CORPORATION OF NEW YORK

TELEPHONE-EXCHANGE SYSTEM

Application filed December 5, 1928, Serial No. 323,805, and in Great Britain December 13, 1927.

This invention relates to improvements in or relating to automatic and semi-automatic systems and apparatus and consists more particularly in improvements or modifications in operators' key sending equipments of the kind provided with registering and impulse sending mechanism.

One of the objects of the invention is to effect an economy in apparatus and a simplification of the circuits without impairing the efficiency of the facilities afforded by the equipment.

One embodiment of the invention specifically set forth comprises an operator's key sending equipment in which a key set is provided connected in permanent multiple relation with all of the link circuits having access to impulse senders and to junction lines, each link circuit being provided with switching means for operatively associating the key set therewith. In addition there is associated with the key set a cancel key whereby a false registration may be canceled prior to its completion and a start key whereby numbers containing less than the maximum number of digits may be employed. The contacts of these keys are connected to the same conductors as the digit keys. Impulse senders are provided having relay registers operating in response to the digit keys to take a registration for controlling the operation of automatic switches and in response to the cancel and start keys to perform other functions. The registration set up by these additional keys differs from those set up by the digit keys: that of the cancel key maintains the connection between the impulse sender and the link circuit while wiping out all registrations and restoring the digit distributing switch to normal; that of the start key advances the digit distributor to the group of positions in which it controls selections and thereafter to the position in which it controls the dismissal of the sender.

The operation of this embodiment of the invention will be more clearly understood from the following description and the accompanying drawings in which:

Fig. 1 shows a junction terminating in a junction relay set JR and having associated

therewith an assignment key ASK and a junction lamp JL. The operator's digit keys 1 to 9 and 0, and an outlet relay set comprising a junction finder JF and a sender finder SF are also shown in this figure.

Figs. 2 and 3 show a registering and impulse sending mechanism.

Fig. 2 should be placed on the right of Fig. 1 and Fig. 3 on the right of Fig. 2 to form a complete circuit diagram.

The "B" operator on receipt of a call allots a junction, and also assigns the junction relay group JR, Fig. 1, tied to this junction by depressing momentarily an associated assignment key ASK. The junction relay group starts up two rotary switches via an outlet relay group, of which there is a small number (3 or 4) per position, a free one being already preselected. The two switches hunt, the junction finder JF to find the assigned junction and the sender finder SF to find a free sender Figs. 2 and 3. Senders are available to all of a group of operators, and when one has been found, the junction lamp JL associated with the assigned junction glows, giving a signal that the call should be set up. (The junction lamp also flickers if the distant operator takes an unassigned junction, giving a signal to the "B" operator.)

The operator then sets up the call by depressing momentarily one at a time digit keys 1 to 9 and 0 corresponding to the number required, and these store the number in the sender, via the outlet group and sender finder. When the set-up is completed, the sender prepares the outlet group for sending out the call. If the distant operator has taken the allotted junction, the sender sends out the call as loop impulses to the automatic selectors, via the outlet group and the junction group. If the operator has not taken the junction, the sender waits for her to do so, and if this has not been done after a certain length of time, clears down all circuits by a time pulse. At the end of sending out, the sender switches the junction group to a through talking connection, and clears down the outlet group and itself. The junction group gives a transmission bridge and supervision to manual exchange and local sub-

scriber, under control of the manual exchange operator.

When a set-up is completed, the outlet group is placed under the control of the sender, and the next free outlet is preselected, ready for another set-up. If an incomplete set-up is made, the call cannot be sent out in the usual manner; it is then cleared out either by a time pulse after a certain lapse of time or by a fresh assignment. Under these conditions the sender sends out the call to a local service operator if the distant manual operator has taken the junction, but clears down all circuits immediately if she has not done so.

The operator may, having set up a wrong number, cancel the set-up and set up the call again, provided a complete call was not set up. This is done by a key on the position.

Where all numbers have not the same number of digits the set-up is completed by depressing a start key on the position after the set-up of any number having less than the maximum number of digits. For a maximum number of digits the key is not used. This caters for a mixed digit area and also for short-numbered service calls, such as phonograms, etc. The sender subsequently sends out the correct number of digits and then clears down.

In the present embodiment the key sending equipment is arranged for four digit (or mixed 1, 2, 3 and 4 digit) numbers, four outlet groups per position, and a maximum of 50 junctions per position, but the invention is applicable to any arrangement of these quantities. The incoming order wire and other operator's circuits are not shown since they do not affect the key sending equipment. The operation of the circuits in greater detail is as follows:

Circuit operation

When the "B" operator assigns a junction, relay AS operates from the assignment key ASK via back contacts B4, and locks to ground at contacts AS5. Relay AS grounds the common start lead at contacts AS7, removed ground from the P contact of the junction finder bank and connects the P contact to relay B at contacts AS4, disconnects the outgoing trunk wires at contacts AS1 and AS2, and connects the junction lamp JL to the outlet groups over a common lead at AS6. If the distant "A" operator has already taken the junction, relay L will be operated from the distant exchange over the positive line and the lamp will be flickering via contacts B5, AS6, L1, B1, and the flicker lead FR; on assignment flickering ceases.

The common start lead is connected to contacts in chain of all outlets. When any outlet is busy, PY relay will be operated (or KK in special circumstances as described later) so that the ground on AS7 operates

relay SJ of the first free outlet, via back contacts SJ5 and KK7 of all outlets, front contacts PY3 of the first busy outlets, back contacts PY3 of first free outlet, and outlet disconnect key ODK. In the present instance it is assumed that the outlet group shown in full is the second outlet, the first outlet group being busy. Relay SJ locks at SJ5 to the same start lead ground via contacts SJ5 and KK7 of preceding outlets in chain, so as to prevent interference to or from other outlets. Relay SJ closes the circuits of junction finder magnet JFDM at contacts SJ2 and sender finder magnet SFDM at contacts SJ4, and circuits of relay KS at contacts SJ3 and relay KJ at contacts SJ1. Both finders hunt, their magnets operating from ground on P bank contacts of busy senders and unassigned junctions respectively. During hunting relay KS is short-circuited by ground on both sides of its winding.

When a free sender is found the magnet SFDM stops, relay KS is no longer short-circuited and operates via outlet disconnect key ODK and contacts SJ3, in series with sender finder magnet SFDM. When the assigned junction, from whose P bank contact ground has been removed at contacts AS4, is found, the magnet JFDM stops. Relay KS at contacts KS3 grounds the sender P bank contact to busy it, lights the outlet lamp OL at contacts KS5 to denote a busy outlet, operates relay KK at contacts KS2 via contacts PY2, connects relay PY to wiper ST and disconnects sender chain wire SC at contacts KS4, grounds one side of the winding of relay KJ at contacts KS5 and prepares ground for the junction P bank contact at contacts KS1. Relay KK switches the sender finder wipers W, X, Y, Z to the digit keys at contacts KK1, KK2, KK3, KK4, lights the junction lamp JL at contacts KK6 over the common lead to the assigned junction group via contacts AS6 and B5, holds relay KS at contacts KK5, and closes another point in the circuit of relay PY at contacts KK7. The junction lamp JL glows as a signal for the operator to set-up the call for that junction. When the assigned junction has been found relay KJ operates via contacts KS5 and SJ1, in series with finder magnet JFDM, locks at contact KJ4, prepares the out-pulsing and control circuits to the junction group JR at contacts KJ1, KJ2, KJ3, prepares an alternative connection for relay PY at contacts KJ6, and grounds the junction P bank contact at contacts KJ5 via contacts KS1 to busy it. From a consideration of the previously described circuits it will be seen that the call can be set up independently of the junction being found.

Relay B in the junction group now operates from the ground on P bank contact via contacts AS4, changes over relay AS at contacts B4 so as to hold it in parallel with relay

5 B, keeps the lamp JL glowing at contacts B5 independently of the outlet group, prepares the output control circuit at contacts B1, and removes ground from the start lead at contacts B6. Relay SJ therefore restores, and prepares a circuit to relay PY via contacts KK7; relays KJ and KS hold.

10 Relay BG, Fig. 2, in the sender operates from ground on the P bank contact via contacts BQ3, connects up relay DS at contacts BG3, disconnects the homing circuit of switch DL at contacts BG1, provides ground at contacts BG4 for relay SS and at contacts BG6 for the storage relays, etc., closes at contacts BG5 a point in a chain circuit which will be completed over similar contacts in the other senders (represented by the dotted connection BE) to transmit earth over lead SC to operate relay PY in the outlet relay group, when all the senders are busy; connects up time pulse lead TP1 at contacts BG7, connects up supervisory lamp SL at contacts BG2, and earths the impulse-motor start wire MS1 at contacts BG8. Relay SZ also operates from contacts BG6 via contacts MB4 and ST3, and prevents the operation of relay CC.

15 There is a group of four storage relays MW, MX, MY, MZ; CW, CX, CY, CZ, etc. Fig 3, for every digit of numbers to be set up; the lower operating windings are wired to the banks of switch DD as shown in the diagram and their contacts are wired in multiple to the banks of switch S. In the drawings, the switch DD is shown wired for a maximum number of 4 digits, and four groups of storage relays are shown. The wiring from banks of DD switch to the windings of the storage relays is shown for the 1,000's group M only, the wiring for the other groups being similar. When the operator depresses a digit key 1 to 9 or 0, Fig. 1, for the first digit, ground is sent forward over one, two or three of the four leads from the keys, via contacts KK1, KK2, KK3, KK4, wipers W, X, Y, Z, first contacts of banks DD6, DD5, DD4, DD3 of switch DD to lower windings of relays MW, MX, MY, MZ of group M (thousands), thence to battery via the common relay DS. The operated relays lock on the upper windings to ground at contacts BG6 via contacts MB4. Relay DS energizes magnet DDM at contacts DS1 and releases when the key is restored, so that switch DD is advanced one step. When the next key is depressed a similar circuit is made for one, two or three relays of the hundreds group C over the second contacts and wires C of switch DD, and similarly for other digits. Thus a four figure number is stored by the sender storage relays. The wiring of the digit keys is arranged so that, with the same arrangement of key springs as is in general use in key sending circuits, no undue spring load is brought on any storage relay.

20 When the complete number has been stored,

(i. e. 4 digits) switch DD will have moved to its fifth position and relay SS is then connected over wiper DD2 to the sender finder ST wiper, so that relays SS and PY operate in series via contacts KS4, sender finder ST wiper, DD bank and wiper 2 and contact BG4. Relay SS locks to contacts BG4 over its lower winding and contacts SS5, grounds the ST wiper at contacts SS6, provides the marking ground for storage relay contacts at contacts SS1, prepares the circuit of relay ST at contacts SS2, closes the out-pulsing loop at contacts SS3 and grounds the release trunk P at contacts SS4. Relay PY disconnects at contacts PY2 and PY3 relays KK and SJ which release. Relay KK disconnects at contacts KK5 relay KS which releases slowly, disconnects the digit keys from the sender finder wipers and connects these wipers to the junction finder wipers at contacts KK2, KK3 and KK4, and disconnects set-up signal lamp JL at contacts KK6. Relay PY now grounds junction finder P wiper via contacts PY1, sender finder W wiper, wiper and bank DD6 and contacts BQ1; in place of contacts KS1. Contacts PY4 hold relay KJ and light outlet lamp OL in place of contacts KS5. Relay KS removes ground from the sender release trunk, which is now grounded by relay SS in the sender, so that the outlet is held by the sender. The operator's peg count meter is operated over lead PM during the release of relay KS via contacts KS2 and PY2. Contacts PY3 and KK7 together remove the start lead from this outlet and switch it to the next free outlet, so that a new assignment can be made.

25 The call now proceeds independently of the "B" operator, and waits for the "A" operator to take the junction, if she has not already done so. When the junction is taken, relay ST in the sender operates via contacts SS2, sender finder Z wiper, contacts KK4, KJ3, springs of outlet disconnect key ODK, junction finder OC wiper, contacts L1, B1 and AS1, (relay L being energized from the distant exchange). Relay ST locks via contacts ST2 to BG6, disconnects relay SZ at contacts ST3, and relay TP (if operated) at contacts ST2; (the opening of contacts ST1 is ineffective at this time). The line relay of the automatic first selector has been operated by the operation of contacts SS3, via contacts SA2, and the loop springs LS in parallel, sender finder wipers X and Y, contacts KK2 and KK3, KJ1 and KJ2, junction finder - and + wipers. This selector returns ground on the first selected release trunk to the junction group to hold relay B of the latter and energize the right hand winding of shunt field relay D. The sender analysis meter is operated over wire AM and contacts ST4 to register an effective call.

30 When relay SZ has released, a circuit is made for relay CC via the magnet impulse springs MGS. The magnet and loop springs

MGS and LS are opened and closed at 10 interruptions per second each, by the motor controlled over contacts BG8. The open period of the loop springs is twice the closed period, similarly to the subscriber's dial, and the magnet springs are closed and open while loop springs are open and closed respectively. When the first closure of magnet springs occurs after release of relay SZ relay CC operates its fly contacts CC1 only via contacts CC4, springs MGS, contacts SZ4 and BG6. When the magnet springs open, a short-circuit is removed from the second winding of relay CC and the relay operates on both windings in series via contacts CC1, connects the magnet springs to the sending switch magnet SDM at contacts CC4, disconnects the latter's homing circuit at contacts CC3, and short-circuits relay RA at contacts CC2. When the magnet springs close again, magnet SDM is again energized, while at the same time the loop springs open and give one pulse to the first selector A relay. When the magnet springs open again the loop springs close, so that the switch S makes one step and the first selector A relay reoperates. Thus a series of impulses is sent out, relay CC and SA remaining operated. The double operation of relay CC ensures that a clipped impulse cannot be applied to the magnet SDM, to save undue wear on its mechanism.

When the correct number of impulses corresponding to the first digit stored has been sent out, wiper 2 of switch S will have arrived at the corresponding contact (counting from the first bank connection), which will be grounded via the operated contacts of the first group M, of storage relays, 5th contact and wiper of bank DD3 and contacts SS1. Relay SZ therefore operates to this ground via wiper S2, locks via contacts SZ3 and SA3, short-circuits the sending loop at contacts SZ2 to prevent further impulsion, and releases relay CC at contacts SZ4; (contacts SZ1 are ineffective at this time). When relay CC has restored, switch S returns home under self-interruption via contacts CC3 to ground via bank S1 and relay RA which relay operates in series. Relay RA gives a slow-operating alarm over lead RA if the switch fails to return home. Relay SA holds in parallel but restores slowly when switch S has returned home. When relay SA has restored, the sending loop is re-short-circuited by SA2, relay SZ is restored slowly at contacts SA3, and magnet DDDM is released so that switch DD steps one. When relay SZ has released, the circuit is again made for relay CC at contacts SZ4, the short-circuit on the sending loop at contacts SZ2 is removed but remains at contacts SA2, and the locking contacts SZ3 are opened.

The same series of operations then proceeds as after the previous release of relay SZ, except that switch DD has moved one

step meanwhile. Relay SZ therefore operates when the switch S has stepped to the contact corresponding to the second digit, since its operating ground will be obtained via the contacts of the second hundreds group, C, of storage relays, lead C, 6th contact and wiper of bank DD3 and contacts SS1. The correct number of impulses for the second digit stored is thus sent out, and so on for the remaining digits. The slow-release times of relays SA and SZ between digits, together with the operating time of relay CC enable the group selectors to hunt for the next switch before the next digit is sent out.

When relay SZ has released after operating for the end of the last digit of the number, a circuit is made for relay BQ, which operates on the upper winding via contacts SZ1, 9th contact and wiper of bank DD3, and contacts SS1. Relay BQ locks at BQ1, grounds the release trunk and disconnects relay BG at contacts BQ3, keeps the chain circuit closed at contacts BQ4, flashes the sender lamp SL at contacts BQ2 over interrupted ground on lead IG to denote clear-down, and removes ground from bank DD6 at contacts BQ1. This last releases relay AS in the junction group, which has been holding via junction finder P wiper, contacts KJ5, PY1, sender finder W wiper, wiper and bank DD6 commoning contacts BQ1. Relay AS on release places the junction group transmission bridge across the group selector to hold it, under control of the "A" operator via contacts L1. Relay B is now held by the group selector release trunk, keeps the junction lamp JL alight at contacts B5, maintains the assignment lead disconnected at contacts B4, and maintains the selector loop through at contacts B1 and B2.

At the same time relay BG releases in the sender, closes the homing circuit for magnet DDDM at contacts BG1, opens the time pulse circuit at contacts BG7, releases relay TP, ST and storage relays and prevents operation of relay CC at contacts BG6, and releases relay PY in the outlet group and relay SS at contacts BG4. Relay PY restores and releases relay KJ and extinguishes the outlet lamp OL at PY4. Relay KJ restores and disconnects the sender from both junction group and outlet group. Relay PY at contacts PY3 reconnects the start lead to relay SJ for a new set-up. Magnet DDDM homes its switch via bank DD1 in series with relay RA, which operates. Relay RA gives the alarm at contacts RA2 if the switch fails to return, and holds relay BQ over its lower winding at contacts RA1. Relay BQ keeps the sender busy at contacts BQ3; the chain circuit closed at contacts BQ4, and the lamp SL flashing at contacts BQ2, until the sender has completely restored to normal, when relays RA and BQ release.

When the called subscriber answers, cur-

rent is reversed back to the junction group so that shunt field relay D operates and at contacts D1 connects the battery winding of relay L to the —ve line, giving supervision to the distant operator. If, however, a busy selector has been found, relay I "flashes" due to the periodic short-circuiting of the selector loop by busy flash from the busy selector. Relay I then connects relay L periodically to the —ve line to flash the distant supervisory lamp, for a busy signal.

The circuits also provide other features as follows:

(a) If the operator, having made a wrong set-up, desires to cancel the set-up and start again, she depresses the cancel key C, which is wired in common with the digit keys. The depression of this key energizes the X and Z relays of the particular storage group on which switch DD in the sender is resting, in the same way as for a digit key. The X and Z combination is not used for a digit, so that it is never made by a digit key. This combination however provides a circuit for relay BQ, which operates on the upper winding via contacts CW3 (back) (assuming that the X and Z combination of the 100's group is energized) CZ6 and CX4 (front) DX4 and UX4 (back) wiper and bank DD1 (any contact 2—4) and relay RA to ground.

Relay BQ releases relay BG at contacts BQ3, and keeps sender chain closed at contacts BQ4. Relay BG on release releases the storage relays at contacts BG6 and disconnects the time pulse at contacts BG7, and completes the homing circuit of magnet DDDM at contacts BG1. The circuit for driving the switch DD to its fifth position extends via magnet DDDM, its interruption contacts, contacts BG1, a chain circuit including back contacts MX4, CX4, DX4, UX4 of all the storage groups, commoned contacts and wiper of bank DD1, and relay RA; in position 5 the magnet DDDM operates via contacts BG1, commoned contacts 5 to 12, and relay RA. Relay RA operates and holds relay BQ via contacts RA1 until the switch is home. Relays RA and BQ then release and relay BG reoperates, in readiness for a new set-up. The time pulse has now been reset, so as to give the operator full time for a new set-up.

(b) If in any area it is desirable to send numbers having a fewer digits than the full number, (such as calls to services or in mixed digit areas) a start key S is fitted on the position. The operator depresses this key after setting up the short number and the W, X and Z combination in the particular storage group on which the switch DD stands are operated in the sender in the same way as for a digit key, this combination being also not used for a digit. Assuming the operator has set a number comprising one digit 65 this operation causes the magnet DDDM to

be energized via its interruption springs, contacts CW3, CZ6 and CX4 (front) DX4 and UX4 (back) bank DD1 and relay RA to ground. Since the storage relays remain locked up as usual, the switch moves only to the position of complete set-up (5th position on the drawing), so that the sender then prepares to send in the usual way. (If a two digit number had been sent this circuit would have extended over contacts DW3, DZ6, and DX4, etc.) When sending commences, the stored digits are sent out, but when wiper DD3 of control switch DD arrives at the contact corresponding to the storage group operated by the start key, it will not mark any point on the bank S2 of switch S, but instead prepares a circuit for relay BQ. Thus, when relay SZ has released after its operation for the previous digit, relay BQ operates on its upper winding via contacts SZ1, CZ2 of the particular storage group concerned, CY2 (back), CX2, CW2, bank and wiper of bank DD3 and contacts SS1 to ground. This causes the sender to clear-down in the regular manner, having sent only the correct number of digits. The junction group then switches through and the outlet group clears down in the usual way.

When all the numbers have the same full number of digits contacts CZ2, DZ2, UZ2, CW3, DW3 and UW3 will not be required the back contacts MX4, CX4, DX4, UX4 will be omitted, the armatures operating contacts MX4, CX4, DX4, UX4 will be connected in parallel and the whole of blank DD1 commoned.

(c) If the operator has made an incomplete set-up, the sender cannot prepare to send and the call therefore has to be cleared out either by—

- (1) Assignment of a fresh call or
- (2) Time pulse.

(1) If the sender has not prepared to send, relay PY has not been operated, relay KK is still operated, and wiper of bank DD2 of switch DD is on a contact before the position of complete set-up (i. e. contacts 1—4). If now the operator assigns a fresh junction group, ground from AS7 energizes relay MB in the sender directly on its upper winding via the common start lead, contacts SJ5 (back), KK7 (front), non-inductive winding of relay PY, contacts KS4, sender finder wiper ST, wiper and bank DD2 and contacts MB1. Relay MB operates its fly contacts MB2 through which the relay operates fully to contacts BG6. Relay MB operates at contacts MB5, relay SS which locks, disconnects at contacts MB4 the storage relays and relay SZ which release, and connects bank DD2 to its magnet DDDM at contacts MB1. Relay SS prepares the sender for sending in the usual way, and the ground via contacts SS6 operates relay PY and also

70

130

magnet DDDM via bank DD2 and MB1. Relay PY prepares the outlet group for sending by disconnecting relay KK at contacts PY2 in the usual manner. Magnet DDDM causes its switch to step to the position of complete set-up (5th contact) where the magnet is then disconnected by the bank commoning, so that the sender is now in the usual start-send position except that relay MB is also operated.

When relay PY has operated and KK released, the ground on the common start lead is switched to the next outlet, which therefore proceeds to function for the new call. A special call is now sent out, depending on the cross-connection on terminal strip MS, and providing that the distant operator has taken the junction. On the operation of relay MB relay SZ releases, and if the operator has not taken the junction when relay SZ has released, relay BQ operates via contacts SZ1, ST1, back contacts MZ5, MY5, MX3, MW2 of first storage group, bank and wiper DD3, contacts SS1 to ground. Relay BQ causes the sender to clear-down in the normal manner, followed by the outlet and junction relay groups. If, however, the distant operator has taken the junction, relay ST operates and locks over the output control circuit, as described for the regular call, so that on release of relay SZ the above circuit for relay BQ is disconnected by contacts ST1. The sender therefore proceeds to send out in the usual way, but the storage groups, being released, provide no marking ground on bank S2 of switch S via their front contacts but ground the terminals 11-14 of terminal strip MS, via all their back contacts MZ5, MY5, MX3, MW2, etc. The MS terminals are cross connected to terminals 1-10, which are commoned to bank S2 of switch S, or to terminal 15. Thus if terminal 11 is connected to terminal 5 the sender will send out a first digit of 5, and so on for other digits. If any terminal 11-14 is jumpered to terminal 15, the relay BQ will be operated via contacts SZ1, MS15, MS11, 12, 13 or 14, back contacts of corresponding storage relays, bank and wiper DD3, contacts SS1 to ground. By this means the sender can be made to clear-down immediately (using connection MS11 to MS15) or after any number of digits, thus leaving the junction group on the first group selector or switching the call to any desired manual operator.

(2) If the operator has made an incomplete set-up but has not reassigned within a given time, the call is cleared out as follows: Time pulse, consisting of a ground pulse at certain intervals of time (e. g. 10 sec.) over wire TP1 is connected to relay TP in the sender by contacts BG7 as soon as the sender has been found. At the first impulse relay TP operates over its upper winding via contacts TP2 and BG7 and closes contacts TP1

only, and when the pulse goes, relay TP operates fully on both windings to ground at contacts BG6 via contacts ST2 and TP1, and changes over the time pulse lead to relay MB at contacts TP2. If the operator sets up the call and the distant operator by taking the junction causes relay ST to energize before the time pulse interval has elapsed, relay TP is disconnected by contacts ST2. If not, the second time pulse operates, via contacts TP2, relay MB, which locks on its upper winding. Relay MB then causes the special call to be sent out or the sender to clear-down in the same manner as in (c) (i). The double operation of relay TP gives the "B" operator at least the time pulse interval in which to set up the call.

(d) If the operator makes a complete set-up, but the distant operator fails to take the junction before the advent of the second time pulse, relay MB operates as before. The special call is then sent out if the distant operator then takes the junction before the release of relay SZ, (which is an unlikely event), or the sender clears-down immediately as described before.

(e) A key is associated with each sender and each outlet group to facilitate testing of the circuits and cutting out of faulty circuits. The outlet disconnect key ODK, when thrown, lights the associated outlet lamp OL, disconnects relay SJ and switches the common start lead to another outlet, and disconnects relay KS. The sender busy key BK connects its lamp SL over the supervisory key SK ground, grounds the sender release trunk and closes the chain circuit in order to keep the sender busied, and disconnects the release alarm and meter leads. The supervisory key SK is common to a group of senders, and when thrown causes the lamp SL of all busy senders to light over contacts BG2.

(f) In order to prevent unnecessary running of sender finders when all senders in the group are busy, a chain circuit is used, connecting all senders of the group by means of contacts BG5, BQ4 and busy key springs in parallel. This chain is completed whenever all senders in a group are busy or out of service, and immediately operates relays PY in parallel of all outlets whose sender finders have access to this group of senders, except those outlets which have found a sender before the chain circuit was completed. Relay PY operates via back of contacts KS4 and KJ6 if a sender has not been found, lights the outlet lamp OL at contacts PY4, and disconnects relay SJ and switches the common start lead to the next outlet, at contacts PY3. If relay SJ was operated by an assignment, it now releases and stops the finders hunting, and the assignment passes to another outlet associated with another (free) group of senders.

What is claimed is:

1. In a telephone system, a key set comprising a single row of digit keys, an impulse sender comprising a plurality of registers, means to set said registers in response to the repeated operation of said key set, means responsive to the setting of all of said registers to initiate a selective operation, an additional key effective to establish a registration upon any one of said registers different from the digit registrations, and means responsive to the establishment of said different registration to initiate said selective operation.
- 5 2. In a telephone system, a key set comprising a single row of digit keys, an impulse sender comprising a plurality of registers, a digit distributing switch for successively connecting said key set to said registers whereby said registers may be set in response to the repeated operation of said key set, means responsive to the setting of each of said registers to advance said digit distributing switch, means controlled by said 10 switch in the position taken following the setting of the last register to control a first selective operation, an additional key effective to establish a registration different from the digit registrations, and means responsive to the establishment of said different registration on any one of said registers to advance said digit distributing switch directly to said selection controlling position.
- 15 3. In a telephone system, a key set comprising a single row of digit keys, an impulse sender comprising a plurality of registers, means to successively connect said key set with said registers whereby said registers may be set in response to the repeated 20 operation of said key set, means responsive to the setting of all of said registers to initiate a selective operation, additional keys effective to establish registrations different from the digit registrations, and means responsive to the establishment of said different registrations to cause said sender to function in a manner different from a normal registration.
- 25 4. In a telephone system, a key set comprising a single row of digit keys, an impulse sender comprising a plurality of relay registers, a plurality of conductors connecting said key set and said impulse sender, means to successively connect said conductors with said registers whereby said registers may be 30 set in response to the repeated operation of said key set, means responsive to the setting of all of said registers to initiate a selective operation, an additional key connected with said conductors and effective to establish a 35 registration upon any one of said registers different from the digit registrations, and means responsive to the establishment of said different registration to initiate said selective operation.
- 40 5. In a telephone system, a key set comprising a single row of digit keys, an impulse sender comprising a plurality of relay registers, a plurality of conductors connecting said key set and said impulse sender, means to successively connect said conductors with said registers whereby said registers may be 45 set in response to the repeated operation of said key set, means responsive to the setting of all of said registers to initiate a selective operation, an additional key connected with said conductors and effective to establish a 50 registration upon any one of said registers different from the digit registrations, and means responsive to the establishment of said different registration to initiate said selective operation.
- 55 6. In a telephone system, a key set comprising a single row of digit keys, an impulse sender comprising a plurality of relay registers, a plurality of conductors connecting said key set and said impulse sender, means to successively connect said conductors with said registers whereby said registers may be 60 set in response to the repeated operation of said key set, means responsive to the setting of all of said registers to initiate a selective operation, an additional key connected with said conductors and effective to establish a registration upon any one of said registers different from the digit registrations, and means responsive to the establishment of said different registration to initiate said selective operation.
- 65 7. In a telephone system, a plurality of digit keys, an impulse sender comprising a plurality of relay registers, means to associate said keys and said registers, means to position said registers under the control of said digit keys, an additional key effective to establish a registration different from digit registrations, and means responsive to said different registration to wipe out said registration without releasing said keys from said sender.
- In witness whereof, I hereunto subscribe my name this 16th day of November, 1928.
- JOHN R. GOULD.
